UNITED STATES PATENT OFFICE

2,202,442

MANUFACTURE OF WIRE FABRIC

Arthur Ernest Blashill, Handsworth,
Birmingham, EnglandApplication February 6, 1939, Serial No. 254,944
In Great Britain February 7, 1938

13 Claims. (Cl. 140—8)

This invention relates to the manufacture of wire fabric of the kind which may be described as square-mesh and which is formed by winding wire, fed from two sources, upon a flat rotary former bar so that a double flattened wire helix is produced along the former and is threaded into engagement with the last helix of the already formed fabric.

A length of the double helix when fed transversely across the already formed fabric is severed from the main supply on the former bar so that each severed length of wire helix may be retained upon the fabric which is advanced in a step-by-step manner for the reception of successive helices. This severing operation gives a barbed-wire effect to the side edges of the fabric which it is necessary to destroy and the invention has for one of its essential objects to provide improved means for turning-over the sharp wire ends and for advancing the movement of the fabric as it is formed.

Further objects and features of the invention will appear from the following description.

In the accompanying drawings:

Figure 1 is a broken plan view of a machine in accordance with the invention.

Figure 2 is an enlarged plan view of the driving mechanism.

Figure 3 is a sectional end elevation of Figure 2, on the line 3—3 of Figure 2.

Figure 4 is an enlarged end view of Figure 1 looking in the direction of the arrow with the bottom part of the machine casing broken away.

Figure 5 is an enlarged plan view of the longitudinally adjustable knuckling head seen on the right in Figure 1.

Figure 6 is an enlarged end view on the line 6—6 of Figure 1 showing one of the star-wheels and its knuckler.

Figure 7 is an enlarged plan view, partly in section, of the knuckler bar seen on the left in Figure 1.

Figure 8 is an enlarged end view of the trip mechanism employed on the machine in connection with the spindle upon which the finished wire fabric is wound, and

Figure 9 is a somewhat diagrammatic view showing, in end elevation, the passage of the wire fabric through the machine.

In carrying the invention into effect in one convenient manner as illustrated in the drawings the improved machine comprises a suitable framework or casing 1 containing the various gears and driving shafts and supported between one end of said casing and a pedestal 2 laterally

spaced therefrom there is provided a transverse sheet or hood 3 (Figures 1, 4 and 9) which serves to guide the fabric, as it is formed, from the helix threading zone to a series of toothed discs or star wheels 4 provided upon an intermittently rotatable shaft 5 extending between said pedestal and the said casing and formed to permit of adjustment of the individual star wheels along the length thereof to suit different widths of fabric. From the said guide plate 3 the fabric passes downwardly to a transverse roller or shaft 6, (Figures 8 and 9), which is mounted at its opposite ends for vertical reciprocatory motion along a toothed rack 7, and after being passed under this roller the fabric passes upwardly and over the star wheels 4, then downwardly again and under a second roller or shaft 8 and is finally wound upon an intermittently rotatable shaft 9.

The driving mechanism includes a main central clutch shaft 10 (Figures 2 and 3), a high speed weaving spindle 11 on one side thereof and a single revolution shaft 12 on the opposite side, all three shafts being conveniently located within the upper part of the said casing at the left hand end thereof as seen in Figure 1. An advantage of employing these separate shafts is that, since the main clutch 25 is provided upon a separate shaft it is possible to limit the high speed weaving spindle 11 to a relatively small diameter so that upon suddenly arresting this shaft, to enable a threaded length of wire helix 13 (Figure 1) to be severed from its main supply, there is no inertia effect tending to cause the spindle to over-run the position in which it is required to be arrested and which would happen if the main clutch was provided upon the high speed weaving shaft, which latter carries the flat former bar 14 about which the wire is wrapped in the form of a flattened helix, two such helices being formed in a single operation and being fed along the former bar for threading into the last helix of the formed fabric.

The wire 15 from which the helices are formed is supplied from two sources and is guided by rollers 22 into a double helical slot 16 in a sleeve 17 fixed within a bush 18. The former bar rotates within the sleeve 17 so that besides being wrapped about and along the bar as a double helix the wire is transversed along the bar and is delivered therefrom into a tube 20 (Figures 1, 4 and 9) in which the double wire helix, delivered from the former bar, is threaded upon the last helix of the portion of the formed fabric already within the tube, the latter having a

longitudinal slot 21 which permits an upward movement of the wire helices as the fabric is formed. A second fixed helically slotted sleeve 23 and bush 24 is provided for equalising the leads of the double wire helix as the same is moved along the former bar.

The main clutch shaft 10 is driven from a main driving shaft 36 through a pinion (not shown) meshing with a gear wheel 37 on the clutch shaft, which latter has a pinion 38 meshing with an intermediate pinion 39 in engagement with a gear wheel 40 loose upon the single revolution shaft 12 so that, when-ever the main driving shaft 36 is rotating, so also will the pinions 38 and 39 and the gear wheel 40 be rotated but the gear wheel 40 will only have a driving connection with the single revolution shaft 12 when a clutch 35 on the single revolution shaft 12 is engaged, while the weaving spindle 11, also, will only be driven when the main clutch 25 is engaged.

Associated with the driving mechanism is an endless chain 26 (Figures 2 and 3) supported upon a sprocket wheel 27 and roller 28 and composed of links of which there are twice as many as the number of full meshes in the width of the fabric to be produced and this chain is driven by equal bevel wheels 29 and by a worm 30 and worm wheel 31 equal in teeth to the chain control sprocket, so that as the worm has two threads each revolution thereof is equal to two chain links whereby it is possible by variations of one link to arrest the weaving spindle at any half-turn. The said chain 26 carries a dog or lug 32 adapted when the dog arrives opposite a trigger 33 (and which will happen when a full length of wire helix has been woven into position) to actuate the trigger to cause the main driving shaft clutch 25 to be disengaged so that the weaving spindle 11 is stopped and the clutch 35 on the single-revolution shaft is simultaneously engaged to cause that shaft to rotate, during which rotation the threaded length of helix will be severed from its supply, the fabric 41 will be advanced the distance of one mesh and the severed ends 42 (Figure 6) of the previously threaded helix will be turned-over, this turning-over operation being followed by movement of the star wheels 4 through the distance of one tooth, which is equal to the mesh of the fabric. The one-revolution shaft 12 may be arranged to operate multiple eccentrics which serve to control the actuation of the wire severing mechanism and also the mechanism employed for turning over the severed ends of the helices, all of which will be described later.

Specifically, the said trigger 33 (Figure 3) may be adapted, when actuated by the chain dog 32, to exert a pull upon a rod or bar 43 loaded by a spring 44 and to which bar there is connected a lever arm 45 having a pin 46 engaging a slot 47 in a pawl 48 pivoted at 49 to the machine casing, the lever 45 being also pivoted at 50 to a further pawl 51 which in turn is pivoted to the casing at 52. When the trigger 33 is actuated the pawl 48 controlling the clutch on the main shaft is moved by the said rod and lever 43 and 45 to engage a tooth 53 of this clutch and so arrest rotation of the main shaft while, at the same time, the other pawl 51 moves out of engagement with a tooth 54 on the other clutch 35 so that the one revolution shaft 12 may then rotate. This shaft 12 is provided with a radial pin or finger 55 which, during rotation of the shaft, strikes a roller 56 situated at one end of a further lever

arm 57 pivoted at 58 on a bracket 59, the other end of which lever 57 is connected with a bell-crank 60 by a link 61 which bell-crank is connected with the trigger rod 43 so that actuation of this bell-crank causes the trigger to be released from engagement with said dog 32, whereupon the said rod returns to permit the main shaft clutch 25 to re-engage and to disengage the one-revolution shaft clutch 35 so that the high speed weaving shaft may again rotate.

Rotation of the weaving shaft moves the dog on the endless chain out of the way of the trigger which, except for the moment when it is tripped by the dog, normally is always maintained in the path of the dog.

Since the clutch on the main shaft rotates at a much greater speed than the clutch on the one-revolution shaft the stop lever for the main shaft clutch may be provided with a simple spring cushion.

The single revolution shaft 12 carries a bevel wheel 62 meshing with a bevel wheel 63 upon a stub-shaft 64 carrying two opposite eccentrics 65 and 66 connected respectively with two rods 67 and 68 (Figures 1, 5 and 7) of which the rod 67 extends to the far end of the machine, and through the medium of a slide 81, (Figure 5), carries at its outer end a knuckler 69, actuated from the eccentric 65 by a pull-action, and the rod 68 terminates on the near side of the machine and carries a knuckler 70, actuated from the eccentric 66 by a push-action.

The inner end of the rod 68 terminates within a sleeve 11 (Figure 7) and is engaged by one end of a spring 72, the other end of which abuts against the stub end 73 of the corresponding eccentric slide 71 and this end of the rod 68 has a pin 74 engaging within an elongated slot 75 in the sleeve which at its inner end is connected to the said stub end by a pin 76. The sleeve is always free to rotate with respect to the slide 71 but normally is capable only of a partial rotary movement due to the engagement of a cam roller 78 within an open ended cam slot 79 in a sleeve 80 fixed upon the machine casing. The cam roller is removably fixed upon the rod 68 and the cam slot is formed with an axial portion which provides for plain axial movement of the rod and an offset portion which permits of the rod making a partial turn during the final part of its movement, when its knuckler 70 is in engagement with a barbed end 42 of the fabric. The other knuckler 69 is carried upon a short rod 82 (Figure 5) and is also capable of being given an axial and partial rotary motion by the engagement of a cam roller 83 within the cam slot 84. This knuckler 69, however, is capable of adjustment longitudinally of the machine to suit the particular width of fabric being produced. The adjustment is effected by removing a pin 85 for locking the slide 81 in an adjusted position upon the rod 67 (the latter having a series of holes 86 giving several adjustable positions of the slide) and traversing the bracket 87 along a rack 88 by the rotation of a pinion 90.

Each knuckler is of forked form and the barbed ends of the wire engage within the fork prongs as shown in Figure 7 so that the barbs are not only bent back upon the outermost wires of the adjacent full meshes of the fabric but, due to the partial rotary motion, are actually closed upon these wires.

The star wheels are essentially two in number and are situated upon their carrying shaft 5 so as to engage with the outside full meshes 91.

(Figure 6) of the fabric and each tooth of these star wheels is provided on its outer face with a lateral protuberance 92 (Figures 6 and 7) which forms an abutment for the junction of the outside full wire meshes with the barbs 42 formed as the result of the severing of successive helices and also provides an effective abutment during the operation of the knucklers. The said protuberances may be constituted by angle or T plates secured to the outer faces of the teeth of the said star wheels. Intermediate the end star wheels there are provided one or more plain star wheels adapted to engage the intermediate meshes of the fabric.

Extending along the fabric receiving side of the said star wheels there is provided a rocker-shaft 93 (Figures 4 and 6) carrying cam fingers 94 adapted to engage the fabric and push the same into engagement with the teeth of the star wheels, the cam fingers being urged into this position by the action of a spring 95 upon a rod 96 connected with the rocker shaft by a link 97.

The shaft 5 carrying the star wheels is arranged to be rotated intermittently when the one revolution shaft 12 is in motion and the shaft 5 (Figures 1 and 4) is driven from a shaft 98, geared to the shaft 12, through a modified Geneva drive 99, 100, 101, and 102 and chain 104 passed around sprocket wheels 105 and 106 on the Geneva wheel 30 and the shaft 5 respectively and a jockey pulley 107, the arrangement being such that the star wheels are stepped ahead one tooth after each knuckling operation and are then held stationary.

Associated with the delivery side of the end star wheels there are conveniently provided means adapted positively to release the fabric from engagement with the star wheels. Such means may consist (Figure 6) of a pair of pointed vertical plates 108 provided one for each star wheel, secured in position so that their pointed upper ends lie within an annular channel 109 (Figure 7) formed between the star wheel teeth and the said angle plates 92 secured thereto, the outer diameter of the channel coinciding with the roots of the teeth. Each plate 108 is disposed to lie within the plane of its respective channel and has its outer edge 110 curved outwardly from the pointed end, which lies within the channel, so that as the fabric arrives at the upper ends of these plates it will be stripped from the star wheel teeth by engagement with the plates.

During the time that the one revolution shaft 12 is rotating the length of wire helix threaded into position upon the fabric and situated within the tube 20 is severed from the main supply by a cutter 111 (Figure 1) comprising blades moved in a transversal direction by an eccentric motion produced as the shaft 12 rotates.

The continuously rotating pinion 40 on the one revolution shaft 12 meshes with a pinion 117 on a shaft 116 carrying a pinion 150 with which a chain 112 engages to continuously rotate a pinion 113 at the other end of the chain and secured upon a friction roller 114 which is carried upon a block 115 slidable upon a fixed guide 118 (Figure 8) under the control of a toggle and link mechanism. This mechanism comprises the toggle 119 the central pivot pin 120 of which engages an elongated slot 151 in a link 121 pivoted at 122 upon a lever 123 carrying a counterweight 124. Fast upon the pivot 125 of the counterweight lever there is a second lever 126 to which there is pivoted a catch lever 127 adapted, by the engagement of a pawl 128 with a notch 129 in the catch lever, to hold the counterweight in a raised

position in which the friction roller 114 is held out of engagement with a wheel 130 fast upon the winding shaft 9 for the finished fabric. The shaft 8, which engages the loop of fabric between the star wheels and the winding shaft 9 has at its opposite ends a pinion 131 which engages a vertical rack 132 and the arrangement is such that when, in the formation of the fabric the shaft 8 arrives at the bottom of the rack 132, the shaft, by engagement with a step 134 on a lever 10 133 connected to a link 135 between the lever 133 and the arm 136 of the pawl 128 (the pawl being constituted by one arm of a bell-crank pivoted at 137) causes the pawl to be released from engagement with the catch lever 127 against the action of a tension spring 138 so that the counter-weight operates to pull down the link 121 which, by engagement with the toggle pin 120, flattens the toggle and so moves the friction wheel into driving engagement with the wheel 130. The shaft 8 serves always to impose a load upon the loop of fabric which it engages, sufficient to provide for a tight winding of the fabric upon the shaft 9 and as the loop of fabric is formed the shaft will travel from the top to the bottom of its rack 132, being returned to the uppermost position as a result of the continued rotation of the winding shaft 9 after the release of the pawl 128. As the shaft 8 reaches the uppermost position on its rack the catch lever 127 will be returned to its raised position in which it will be retained by a re-engagement of the pawl 128 when the uppermost position of the shaft is reached. The friction roller will then be out of engagement with the wheel 130 and rotation of the winding shaft is interrupted.

While the machine is adapted to turn over the wire barbs it is possible to eliminate this operation of the knuckler 70 by removing a shear pin 139 connecting the rod 68 with the sleeve 71, removing the cam roller 78 from engagement with the cam slot 79 and connecting a chain 140 between a sprocket 141 on a spine 142 on the rod 68 and a sprocket 143 on the one revolution shaft 12. The rod 68 is then free to make a number of complete revolutions to twist the junction of each barb when, as a result of the forward axial movement of the rod 68 by its eccentric 65, the knuckler 70 engages the barb but the knuckler is inoperative to bend the barbs inwards due to the resiliency offered by the spring 72, with respect to which the rod 68 is now free to move axially within the sleeve. This twisting operation serves to lock the edge of the fabric but with the barbs still exposed.

Having thus described my invention what I claim as new and desire to secure by Letters Patent is:

1. Machine for manufacturing wire fabric of quadrangular or square mesh comprising in combination a coiling worm in which lengths of wire fed from two sources are wound into zigzag form, a flat rotary former bar upon which the wire is wound for threading through the last rows of mesh of the finished fabric, means engageable within the outer meshes of the fabric and means adapted to bend back the barbed ends of the fabric while the latter is engaged by the first said means, the latter being adapted to form an abutment for the bending operation and the said wire engaging means comprising toothed or star wheels with which the wire meshes engage like a chain and sprocket, where the fabric constitutes the chain.

2. Machine as claimed in claim 1 wherein each

tooth of each star wheel is provided with a lateral protuberance forming an abutment for the junction of the full wire meshes of the fabric with the barbs.

5. Machine as claimed in claim 1 wherein the means for bending back the wire barbs comprises a prong member reciprocable upon the junction of a barb with its full mesh to bend the barbs back and rotatable to fold the barbs against the 10 wires of the said full mesh.

6. Machine for manufacturing wire fabric of quadrangular or square mesh comprising in combination a coiling worm in which lengths of wire fed from two sources are wound into zigzag 15 form, a flat rotary former bar upon which the wire is wound, the zigzag wire being threaded through the last rows of mesh of the finished fabric, a pair of star wheels engageable with the outside full meshes of the formed fabric, means 20 for effecting intermittent rotation of the star wheels and prong members reciprocable upon the junction of each barb with its full mesh to bend the barbs back and rotatable to fold the bars against the wires of the said full mesh.

25. A machine as claimed in claim 4 wherein the star wheels are arranged so that the fabric passes over the star wheels and the star wheel teeth are formed to engage one within each full mesh of the upper portion of the wire fabric.

30. 6. Machine as claimed in claim 4, comprising means adapted to engage the fabric and urge the same into contact with the teeth of the star wheels.

7. Machine as claimed in claim 4, comprising 35 means on the delivery side of the fabric adapted to strip the latter from engagement with the teeth of the star wheels.

8. Machine as claimed in claim 4, comprising means adapted to maintain loops in the fabric on 40 either side of the star wheels and to impose a yieldable load upon the loops.

45. 9. Machine as claimed in claim 4 comprising a shaft upon which the finished fabric is wound, means adapted to maintain a loop in the fabric between the star wheels and the said shaft and a latch mechanism operable to permit intermittent rotation of the winding shaft, the actuation of said latch mechanism being under the control of the means which engage the fabric to 50 maintain the said loop.

10. A machine for manufacturing wire fabric

of quadrangular or square mesh comprising in combination a coiling worm in which the wire is wound into zigzag form, a rotary former bar upon which the wire is wound, a first shaft carrying the said former bar, a main driving shaft 5 separate from said first shaft, a second and separate shaft driven from the main shaft, clutch means on said main shaft adapted to permit of alternate operation of the former bar and the said second shaft, and trip mechanism actuated from the former bar and adapted to control the setting of said clutch means.

11. A machine for manufacturing wire fabric of quadrangular or square mesh comprising in combination a coiling worm in which the wire 15 is wound into zigzag form, a rotary former bar upon which the wire is wound, a first shaft carrying the said former bar, a main driving shaft separate from said first shaft, a third and single revolution shaft, gear means connecting the 20 main driving shaft with the said first and third shafts, clutch means on said main shaft adapted to permit of alternate operation of the former bar and the third shaft, trip mechanism actuated from the former bar and adapted to control the 25 setting of said clutch means, and a separate clutch means incorporated in said third shaft and adapted to govern the rotation thereof.

12. A machine as claimed in claim 11 comprising an endless chain driven from the main driving shaft and having a dog or lug thereon, a trigger adapted, when the dog or lug arrives opposite the same, to cause the main driving clutch to be disengaged and the clutch on the one revolution shaft to be simultaneously engaged. 35

13. Machine as claimed in claim 11 comprising an endless chain driven from the main driving shaft and composed of links of which there are twice as many as the number of full meshes in the width of fabric to be produced, sprocket 40 wheels engaging the chain and including a driving sprocket, a worm wheel in driving connection with the main driving shaft and the said driving sprocket, the said chain having a dog or lug thereon and a trigger adapted to be engaged 45 by the said dog or lug to cause the main driving shaft clutch to be disengaged and the clutch on the one revolution shaft to be simultaneously engaged.

ARTHUR ERNEST BLASHILL. 50
